JUICE STRAINER

Application filed February 6, 1926. Serial No. 86,612.

This invention relates to cane mills, and more particularly to an improved juice strainer and trash elevator for such mills. In the operation of such devices, as the mass of cane passes through the various sets of rollers or mills, a certain amount of juice is expressed therefrom by each mill, this juice dropping from the rollers upon a pan from which it flows to a central trough. A certain amount of trash or pulp will also drop upon the pan and be carried into this trough with the juice. The juice and trash thereupon flows through certain chutes provided therefor, upon suitable strainer plates where the juice is strained and caught in suitable containers after passing through such plates. Conveyors are mounted above the strainers upon flights on which are suitable slats or the like, designed to sweep the strainer plates and carry the trash thereover and up an inclined platform to elevate it and deliver it to a suitable conveyor by which it is returned to the mills so as to be again passed therethrough, and any remaining juice will thus be expressed from this trash.

When the strainer or a part thereof becomes worn, or when, for any reason it becomes necessary to repair or clean the same, the mill must be stopped, together with the trash elevator and conveyor, while such work is being performed. This necessarily results in a considerable loss of valuable grinding time. It is desirable, therefore, to have the strainer so constructed that any repair thereto likely to be necessary may be made in the shortest possible time, and the strainer must be strong and durable and constructed so that all joints will be tightly closed.

One object of my invention, therefore, is to provide a juice strainer of a sectional type, so constructed that the various sections may be removed laterally and new sections substituted therefor.

A further object of my invention is to provide a sectional juice strainer whereby the various sections thereof may be joined together and to the associated structure of the trash elevator in a manner which obviates the possibility of any leakage of juice

through the joints and at the same time each section may be readily removed laterally from the strainer when it is desired, and a new section substituted therefor.

A further object of my invention is to provide a sectional juice strainer whereby a defective section may be removed laterally from the strainer and a new section substituted therefor, with a minimum expenditure of time and effort, and further, the new strainer section may be tightly secured in place by a simple and effective arrangement provided for this purpose.

To these and other ends, the invention consists in the novel features and combination of parts to be hereinafter described and claimed.

In the accompanying drawings:

Fig. 1 is a top plan view, partly in diagram, of a cane mill embodying my improvements, certain parts having been omitted for the sake of clearness;

Fig. 2 is a side elevational view of the mill shown in Fig. 1;

Fig. 3 is an enlarged side elevational view of the juice strainer, trash elevator and accompanying structure;

Fig. 4 is a sectional view on line 4—4 of Fig. 3;

Fig. 5 is a top plan view of one of the juice strainer sections;

Fig. 6 is a fragmentary view of a modified form of a strainer frame;

Fig. 7 is an enlarged fragmentary side elevational view of the juice strainer and accompanying parts;

Fig. 8 is a fragmentary sectional view through the juice strainer;

Fig. 9 is a side elevational view of one of the supports for the strainer plates;

Fig. 10 is a top plan view of the same;

Fig. 11 is an enlarged view of one of the trash elevator slats;

Fig. 12 is a sectional view on line 12—12 of Fig. 11.

Fig. 13 is an enlarged view of part of Fig. 8. The preferred embodiment of my invention which I have selected to illustrate and describe, as shown in Figs. 1 and 2, comprises a cane mill 10, provided with pre-

100

crushing rolls 11, followed by a number of juice expressing mills 12, 13, 14 and 15. These mills will in practice usually consist of three rolls, as shown in Fig. 2, the upper 5 roll only being shown in Fig. 1, so as to reveal the underlying parts of the structure. While I have shown only one pair of crushers and four sets of mills in the drawing, it will, of course, be understood that the number 10 of pairs of crusher rolls or the number of sets of three roll mills may be varied according to the particular requirements of the installation. Suitable intermediate carriers 15 16, 17 and 18 are provided to convey the mass of cane from one mill to the next, which carriers may be of any preferred type, the particular structure of which is of no concern in connection with the present invention. The mass of cane will generally fall by gravity 20 from the precrushing rolls to the first mill.

As the crushed cane or bagasse passes through the various successive mills a quantity of juice will be expressed therefrom by 25 each of the mills in turn, in accordance with the usual practice. This juice falls upon the inclined platforms or pans 19 and 20, from which it flows into the trough 21. At the same time, a part of the crushed cane or a 30 certain amount of trash may drop from the rolls upon the pans and be carried into the trough 21 with the juice.

This trash and juice then passes downwardly through inclined chutes 22, 23 and 23^a, the 35 delivery ends 24, 25 and 25^a of which are disposed above the juice strainer designated in its entirety by the numeral 26, in Fig. 2. The first of these chutes 22 is positioned between the second and third mills in the particular arrangement shown, so that this chute will carry only the juice resulting from the work of the crusher, first and second mills before the bagasse has been treated with water, as is usually done to assist in the juice 40 extraction. Just rearwardly of the chute 22 the trough 21 is provided with a partition 21^a so as to keep separate the juice from the first two mills and crusher and the third and fourth mills, and a partition 21^b to separate 45 the juice expressed by the third and fourth mills from those which follow. It will be understood that the juice from the third and fourth mills is carried by the chute 23, and that from the following mills, (not shown) 50 by the chute 23^a.

As shown in Figs. 3 and 4, the strainer structure comprises a trough or tank 27, channel shaped in cross-section to catch and retain the juice. As shown, this trough is 55 separated into sections connected together by the end flanges 28 and 29 on these sections, the interior of the tank being divided by partitions 30 so as to keep separate the juice conveyed to the strainer through the chutes 22, 23 and 23^a. Each of the tank divisions is

provided with an outlet 31 from which the juice may be carried to the storage tank in the usual and well known manner. This tank may be supported upon the blocks 32 which rest in turn upon the bed 33.

The tank sections are provided at spaced points with brackets 34, upon which are designed to rest the strainer supporting beams 35, shown more especially in Figs. 7, 8, 9 and 10. These beams are of sufficient length to span the juice tank and are provided with end bases 36 and 37, to rest on the flanges 34 and to be bolted thereto. The sectional shape of these beams between the bases is shown more especially in Fig. 8, the beam comprising a central web 38 from which project on each side lower lateral flanges 39 and upper lateral flanges 40, forming between them grooves 41 and 42, which as explained hereinafter serve as guideways for the insertion of the strainer sections. Upon the ends of the upper flanges 40 are positioned blocks 43 and 44 to which are secured angle members 45 to which the side plates of the trash elevator structure are secured. Referring to Figs. 9 and 10, it will be apparent that the flanges 39 are longer than the flanges 40, the web portion of the beam between these flanges being beveled, as shown at 46 and 47. Such construction permits easy entry of the strainer sections into the grooves 41 and 42, as will be hereinafter described.

As best shown in Fig. 4, the side plates 48 and 49 of the trash elevator structure, are secured to the angle plates 45 and are provided at their upper and lower edges with laterally extending flanges 50 and 51. In these side plates are journaled shafts 52, 53, 55, 56 and 57, carrying sprocket wheels 58 and 59 over which are trained the chains 60 of the trash elevator. These chains are connected at suitable intervals by slats 61 which are designed to sweep the juice strainer and carry the trash up the inclined platform 62, where it is returned to the cane mill between the first and second three-roll mills by means of the conveyor 63. The conveyor 63 is provided with a pulley 64, driven from the head shaft 65 of the trash elevator, which is in turn driven by a pulley 66 connected to a shaft 67 through a clutch 68. The shaft 67 is driven from the pulley 69, which in turn may be driven from any suitable source of power.

The elevator slats 61, as shown in Fig. 12, consist of a block 70 of wood or the like, secured to the chain 60 by means of the plates 71. To the block 70 is secured a sweeper 72 of rubber or the like, upon the face of which is a copper strip or plate 73, the securing bolts 74 passing through the wood block and through this plate.

The juice strainer is located above the juice tank and is constructed of a number of sections, the sections being withdrawable later-

ally from the frame-work by which they are supported and independently secured in place. Four of such sections are shown in Fig. 3 of the drawings, at 75^a, 75^b, 75^c and 75^d, respectively, all of which are substantially alike and are supported by the supporting beams 35, which rest upon the juice tank. One of these strainer sections is shown in Fig. 5, and consists of a frame upon the upper surface of which is secured the strainer plate or screen 75. The frame is composed of a pair of side angle pieces 76 and 77, end pieces also L-shaped in cross-section 78 and 79, and intermediate lengthwise stringers 80, 81 and 82, suitably braced at their central portions by a cross strut 83. Upon the outside of the end angle pieces 78 and 79 are secured straps or cleats 87 and 88, the upper edges of these cleats being slightly below the upper edge of the end pieces.

In assembling the strainer sections, the edge of the frame with the strainer plate secured thereto is placed upon the flanges 39 of the cross-beam 35, and the frame is then slipped into position above the tank, the cleats 87 and 88 riding into the grooves or channel shaped guideways 41 and 42. The width of these cleats is slightly less than the height of the grooves. Bolts 88^a are then passed through the openings 89 and 90 in the horizontal portions of the side members 76 and 77 and through openings in the angle members 51, secured to the side plates 48 and 49, and the strainer plates drawn upwardly into close contact with the flanges 51 when the nuts are drawn up upon these bolts. The cleats then fit closely against the under surface of the flanges 40 and form a tight joint at that place, while a tight joint is also made between the side members 76 and 77 and the flanges 51. A slight opening or space may be left between the lateral faces of the flanges 40 and the end pieces 78 and 79, but any such space will soon become filled with minute particles of the trash, so that all of the juice which reaches the tank must pass through the strainer plates 75.

It will be apparent that to remove any one of the strainer plates so that another may be substituted therefor, it is only necessary to back the nuts from and remove the bolts 88^a so that the strainer section will drop downwardly upon the flanges 39 and may be freely slipped from its position above the tank in a lateral direction, and a new section substituted therefor. As the flange 39 is longer than the flange 40 and projects beyond the latter flange at both ends, it will be obvious that the strainer sections may be readily inserted within the grooves 41, it only being necessary to position the edge of the section upon the projecting end of the flange 39 and then push it into place within the groove. Moreover, as the grooves 41 are open at both ends the strainer sections may be inserted

into and removed from the grooves from either side. When the strainer section which is to be removed has been loosened, and the new section has been positioned in the grooves 41, as the latter is pushed in place it will displace the old section driving it out of the grooves on the other side of the strainer. This substitution of a new section for an old one may be effected in this manner without stopping the flow of juice or the drag conveyor.

In Fig. 6 of the drawing I have shown a supporting frame for the strainer plates of somewhat modified form in that the side members 76 and 77, instead of being provided with bolt eyes or perforations are provided with slots 91 so that the bolts may be more easily inserted therethrough.

While I have shown and described a preferred embodiment of my invention, it will be understood that it is not to be limited to all the details shown but is capable of modification and variation within the spirit of the invention and within the scope of the appended claims.

What I claim is:

1. In a sugar cane mill or the like, a juice tank, a trash conveyor provided with side walls, said conveyor being spaced from said tank, a plurality of laterally removable strainer sections between said tank and trash conveyor, means for clamping said strainers against the side walls of said conveyor and means for supporting said strainers while being removed.

2. In a sugar cane mill or the like, a juice pan, a trash conveyor above the juice pan and spaced therefrom, a juice strainer between the conveyor and pan, said strainer comprising a plurality of strainer sections, means for releasably securing said sections in fluid-tight contact with the trash conveyor, means for supporting said sections in position between the conveyor and pan and out of contact therewith upon release of the securing means, said sections being freely movable into and out of position beneath the conveyor when so supported.

3. A composite juice strainer for sugar cane mills, comprising a plurality of strainer sections disposed in juxtaposed relation longitudinally of the strainer, and means for securing said sections together whereby each may be removed from or inserted into the strainer individually and in a lateral direction, said securing means including a plurality of cross-beams one between each section, each of said cross-beams being provided with a longitudinal flange at the upper edge thereof, and each of said strainer sections being provided with a flange on the lateral face thereof, said last named flanges being carried below the upper surface of the strainer section a distance equal to the thickness of the first named flanges.

4. A juice strainer structure for cane mills, comprising a pair of spaced frame members, a plurality of strainer sections secured individually to said frame members and disposed in end to end relation, the means securing said sections to said members permitting certain of said sections to be individually removed from and inserted into the strainer in a lateral direction and means normally spaced from said strainer sections on which said sections may rest while being removed.

5. In a sugar cane mill or the like, a juice tank, a trash conveyor above said tank, a juice strainer between the conveyor and tank comprising a plurality of strainer sections, and means for securing said sections in place individually, including a plurality of cross-beams mounted between the tank and conveyor, said sections engaging said cross beams slidably, and means for clamping the strainer sections in place with the upper surfaces thereof substantially flush with the upper edges of the beams.

6. In a sugar cane mill or the like, a juice tank, a trash conveyor above said tank, a juice strainer between the conveyor and tank, said strainer comprising a plurality of detachable strainer sections, means for securing said sections individually in place below the conveyor, and supports below the strainer sections, said supports being adapted to be engaged by said strainer sections upon the latter being detached for withdrawal from below the conveyor.

7. In a sugar cane mill or the like, a juice tank, a plurality of cross-beams disposed transversely of said tank at the top thereof, a strainer comprising a plurality of strainer sections adapted to slidably engage said beams, and means for securing said sections in place between said cross-beams, with the ends of the sections abutting the lateral faces of the beams whereby said strainer sections and beams form a closely assembled strainer structure.

8. In a cane mill or the like, a juice tank, a plurality of cross beams mounted transversely above said tank, a plurality of strainer sections mounted one between each cross beam at the upper edges thereof, means for securing said strainer sections in position between said beams with the upper surfaces of the sections substantially flush with the upper surfaces of the cross beams, whereby a complete strainer is provided having a substantially smooth upper surface, and means on said beams engageable by said sections to support the latter for movement in a transverse direction upon release of the sections from said securing means.

9. In a cane mill, a juice tank and a trash conveyor structure mounted above said tank, a sectional juice strainer, and means for securing the sections thereof individually in place between the trash conveyor and tank

comprising a plurality of cross-beams mounted above the tank, said cross-beams having supporting shoulders, and means permitting the insertion of said strainer sections laterally into place while supported on said shoulders.

10. In a cane mill or the like, a juice tank, a sectional juice strainer positioned above said tank, a trash conveyor disposed above said strainer, and common means for supporting said strainer sections and conveyor, comprising cross-beams mounted transversely of the juice tank and disposed at the joints between said strainer sections.

11. In a sugar cane mill or the like, a trash conveyor, a plurality of strainer sections, means for releasably urging the sections into fluid-tight contact with the conveyor, and means for supporting the sections for free movement from under the conveyor upon being released from contact therewith.

12. In a sugar cane mill or the like, a juice tank, a trash conveyor above said juice tank, means forming a rigid interconnection between the juice tank and conveyor, a juice strainer between said tank and conveyor, said juice strainer comprising a plurality of strainer sections in end to end relation, and means for supporting said sections for lateral movement under the conveyor while the latter remains rigidly connected to the tank.

13. In a cane mill or the like, a juice strainer, said strainer comprising a plurality of strainer sections, and means for securing said sections in place comprising a plurality of transversely disposed supporting members, said supporting members being provided with facing grooves and projecting flanges at the top of said grooves, and said strainer sections being provided with end projecting members designed to lie in said grooves and to abut the lower edges of said flanges and means for urging said members against said flanges whereby a tight joint is made between the strainer sections and said members.

14. In a cane mill or the like, a juice strainer, said strainer comprising a plurality of strainer sections, and means for securing said sections in place comprising a plurality of transversely disposed supporting members, said supporting members being provided with upper and lower projecting flanges and facing grooves between said flanges, said grooves being adapted to receive said strainer sections while the latter are resting upon the lower flanges and projections upon the ends of said strainer sections designed to enter said grooves, and means for securing said sections in place with said projections disposed closely against the undersurface of the upper flanges.

15. In a cane mill or the like, a juice strainer, said strainer comprising a plurality of strainer sections, and means for securing said sections together in end to end relation, com-

prising a plurality of suitably supported transversely disposed supporting members arranged at the joints between said sections, said members having laterally projecting flanges at the upper ends thereof designed to abut against the ends of the strainer sections, and a projecting member on the ends of the strainer sections designed to lie below said flanges and in close contact therewith, and means for securing said sections in place in close contact with said flanges.

16. In a cane mill or the like, a juice tank, a trash conveyor above said tank including spaced side frames, transversely disposed supporting members above said tank, a plurality of strainer sections, said supporting members having lateral flanges upon which said strainer sections may be received and supported, and means for securing said strainer sections individually to said side frames above said flanges.

17. In a cane mill or the like, a juice tank, a trash conveyor above said tank including spaced side frames, a plurality of strainer sections, and means for securing said sections in place between the conveyor and tank, comprising a plurality of transversely disposed supporting members, said members having facing guideways open at their ends to receive said sections, and flanges above and below said guideways, the lower flanges being adapted to receive and support the strainer section when inserted into place, and means for thereafter drawing said strainer section in close contact with said side frames and in close juxtaposed position with said upper flanges.

18. In a cane mill or the like, a juice tank, a trash conveyor above said tank including spaced side frames, transversely disposed supporting members above said tank, a plurality of strainer sections, said supporting members having lateral flanges upon which said strainer sections may be received and supported and upper flanges forming guideways with said lateral flanges, projections on the ends of said strainer sections adapted to enter said guideways, and means for securing said strainer sections loosely against the lower edge of the side frames with said projections closely abutting the underside of the upper flanges.

19. In a cane mill or the like, a juice tank, a trash conveyor mounted above said tank, said conveyor including spaced side frames, means for supporting said side frames including transversely disposed supporting members mounted on the tank, and strainer sections insertable laterally between said supporting members and secured to said spaced side frames with their ends abutting the lateral faces of the transversely disposed supporting members.

20. In a sugar cane mill or the like, a trash conveyor provided with side walls, a juice

tank, a plurality of laterally removable strainer sections between said tank and trash conveyor, means for securing the ends of said sections against movement from between the tank and conveyor, and means engageable by the sides of said sections upon release of the securing means to support the sections during the removal thereof.

21. In a sugar cane mill or the like, a juice tank, a trash conveyor, a plurality of laterally removable strainer sections between said tank and conveyor, beams on which said sections may be moved into and out of position between said tank and conveyor, and means independent of said beams for securing the sections in place between the tank and conveyor.

22. In a sugar cane mill or the like, a juice tank, a trash conveyor, a plurality of laterally removable strainer sections between the tank and conveyor, ways on which the sections may be supported for movement into and out of position between the tank and conveyor, and means independent of said ways for clamping the sections immovably in place between the tank and conveyor.

In witness whereof, I have hereunto set my hand this 29th day of January, 1926.

THOS. M. NALON.
